United States Patent Office

Des. 180,687
Patented July 23, 1957

180,687

PERFUME BOTTLE HOLDER OR SIMILAR ARTICLE

Oliver Flower, Azusa, Calif., assignor to Max Factor &
Co., Los Angeles, Calif., a corporation of Delaware

Application March 15, 1956, Serial No. 40,627

Term of patent 14 years

(Cl. D86—10)

Fig. 1

Figure 1 is a front elevational view of my novel design for a perfume bottle holder or similar article.

The dotted line showing in Figure 2 of the drawing is for illustrative purposes only.

I claim:

The ornamental design for a perfume bottle holder or similar article, substantially as shown and described.

No references cited.
